UNITED STATES PATENT OFFICE.

WILLIAM R. KINNEY, OF READING, MICHIGAN.

HUB FOR ROTARY COLTERS.

1,388,577.

Specification of Letters Patent. Patented Aug. 23, 1921.

Application filed March 25, 1920. Serial No. 368,520.

To all whom it may concern:

Be it known that I, WILLIAM R. KINNEY, a citizen of the United States, residing at Reading, in the county of Hillsdale and 5 State of Michigan, have invented certain new and useful Improvements in Hubs for Rotary Colters, of which the following is a specification.

The invention relates to colters and more 10 particularly to the hub structure whereby a minimum resistance is offered to the rotation of the colter and whereby sand, dust and moisture are prevented from entering the bearing and causing undue wear of the 15 relatively moving surfaces and whereby ample provision is had for lubricating the wearing parts.

The drawings illustrate a preferred embodiment of my invention. However, it is 20 to be understood that in adapting the same to meet different conditions, various changes in the form, proportion and minor details of construction may be resorted to without departing from the nature of the invention 25 as claimed hereinafter.

Referring to the drawings hereto attached:—

Figure 1 is a sectional detail of the hub structure of a rotary colter constructed in 30 accordance with and embodying the essential features of the invention.

Fig. 2 is a sectional detail of a portion of the axle and roller bearing.

Corresponding and like parts are referred 35 to in the following description and indicated in both views of the drawings by like reference characters.

The numeral 1 designates the rotary colter which is of ordinary disk form. The 40 hub comprises companion sections 2 and 3, each comprising a hollow centrally disposed portion and an outer flange portion 4. The hub sections are disposed upon opposite sides of the colter 1 and are secured thereto 45 by means of bolts 5 which pass through registering openings in the flanges 4 and colter 1. An axle 6 passes through openings in the outer ends of the hollow portions of the hub sections. The walls of the open- 50 ings through which the axle 6 passes, are grooved to receive a packing 7 whereby dust and moisture are excluded and the lubricant prevented from escaping. A cap 8 is fitted to the hollow portion of each hub section 55 and is pinned or otherwise secured to the axle. A suitable standard or support 9 re-

ceives the axle 6 and forms sustaining means therefor and the colter mounted thereon.

The inner portion of the opening of the hub is enlarged to receive a roller bearing 60 which may be of any preferred construction and which as shown comprises a sleeve 10, rollers 11 and retaining rings 12. The sleeve 10 fits snugly within the enlarged opening of the hub and is apertured as indicated at 13 to provide free passage of lubricant from the oil chamber to the bearing. The oil chamber is indicated at 14 and consists of an enlargement of the hub opening. The openings of the hub sections are enlarged at their inner ends and the eye or opening of the colter 1 is of like diameter. These several parts result in the formation of the oil chamber 14 when the parts are 70 assembled. An opening 15 extends outwardly from the oil chamber 14 and is provided in the outermost section 3 and is supplied with a yielding closure 16 of well known construction whereby oil may be supplied to the chamber from an oil can without admitting dust, moisture or foreign matter finding its way into the oil chamber. 75

The construction is such as to admit of the parts being readily assembled or disassembled and in operation the colter is free 85 to rotate with a minimum amount of resistance and the wearing parts are kept lubricated and are prevented from excessive wear because of the structure whereby foreign matter is excluded from entering the bearing. 90

Having thus fully described my invention what I claim as new and desire to secure by Letters Patent, is:—

1. In combination a colter, hub sections 95 at the sides of the colter, each consisting of a hollow portion and a flange, the outer ends of the hollow portions having openings to receive the axle and the walls of the said openings being grooved to receive a packing, the hub opening being enlarged to receive a roller bearing and further enlarged to provide an annular oil chamber from which extends a feed opening in which is fitted a normally closed element and a roller 100 bearing disposed within the enlarged portion of the hub opening. 105

2. A hub structure for rotary colters comprising a pair of sections, means for clamping said sections in engagement with 110 a colter, each section comprising a hollow portion, an axle extending through said

hollow portions, elongated rollers positioned within said hollow portions and interposed between said axle and the body of said sections, packing means carried by said sections and tightly engaging said axle for constituting a seal therefor, said sections being further enlarged for providing an annular oil chamber and having a feed opening for permitting the insertion of lubricant 10 therein.

3. In combination with a colter, a plurality of hub sections said hub sections adapted to receive an axle, packing means carried by the ends of said hub sections and 15 constituting a seal therefor, said hub sec-

tions provided with enlarged openings, roller bearings extending longitudinally of said openings and longitudinally of said axle, a further enlarged opening arranged substantially intermediate the ends of said 20 roller bearing, and one of said sections provided with a port for facilitating the feeding of lubricant to said last mentioned enlarged opening.

In testimony whereof I affix my signature 25 in presence of two witnesses.

WILLIAM R. KINNEY.
